MANUALLY CONTROLLED ELECTRO-HYDRAULIC SYSTEM FOR AIRCRAFT

Stanley George Glaze, Brierley Hill, England, and Charles Philip Smith, Ramsey, Isle of Man, assignors to H. M. Hobson, Limited, London, England, a British company

Application December 14, 1955, Serial No. 553,130

Claims priority, application Great Britain December 17, 1954

4 Claims. (Cl. 60—97)

This invention relates to a power operated flying control system for aircraft of the kind in which a pilot's control member controls by means of an electrical signalling system the position of the input member of a servo motor for actuating a control surface of the aircraft.

With a view to safeguarding against the contingency of failure of electrical signalling systems, the invention provides a system of the above kind in which the servo motor is constituted by a tandem hydraulic jack, each section of said jack having at least two independently movable control valves each of which is actuatable by the pilot's control member through the agency of an associated electromechanical transducer mechanism.

This system has the advantage that, as explained later if a control valve of one section of the jack should stick in an open position the other control valve of that section together with the control valves of the other section of the jack assume positions that will cancel a tendency of the servo motor to run away on a resultant output load basis.

Preferably, as in the case of the system described in U. S. application Serial No. 553,124, filed December 14, 1955, the pilot's control member is arranged to operate at least three electrical signalling systems, the signals from all the signalling systems being fed to each of the transducer mechanism. In the event of an electrical failure in one signalling system the other two will then be able to exert majority control over all of the control valves.

One embodiment of the invention will now be described in more detail, by way of example, with reference to the accompanying drawing in which:

Fig. 1 is a diagram showing the servo motor and associated electrical signalling systems,

Fig. 2 is a circuit diagram and

Fig. 3 is a front view of one of the transducers with its cover plate removed.

The control surface 1 is operated by a tandem hydraulic jack comprising fixed pistons 2, 2A accommodated in cylinders 3, 3A in a movable cylinder block 4 coupled to the control surface. The two sections of the jack are respectively controlled by control valves 5, 5' and 5A, 5'A associated with pressure inlets 15, 15', 15A and 15'A and exhaust outlets 11, 11', 11A, 11'A. The control valves, on movement from the neutral position shown, establish in well known fashion alternative pressure and exhaust connections to the ends of the two sections of the jack to cause the cylinder block 4 to move in a direction and to an extent determined by the movement of the control valves.

The control valves are actuated by electromechanical transducers 6, 6', 6A, 6'A respectively. The transducers are of the character described in U. S. application Serial No. 549,737, filed November 29, 1955, and each comprises as shown in Fig. 3 a rotary armature 20 coupled

2

to the associated control valve by an arm 21 and a link 22 and movable between two pole pieces 23 around which are wound three coils 12, 13, 14. The pilot's control lever 7 actuates, when displaced, potentiometers 8, 8A, 8B of three electrical signalling systems including amplifiers 9, 9A, 9B. The signals from all the amplifiers are fed, as shown, to each of the transducers. Thus the signals from the amplifier 9 are fed through the coils 12, 12A, 12'A and 12' in series. Potentiometers 10, 10A, 10B actuated by movement of the cylinder block 4 provide feed back signals to the amplifiers.

As shown in Fig. 2, each electrical signalling system includes an individual source of electric power indicated diagrammatically by a battery 13, for energising the amplifier 9 and its associated potentiometers 8, 10. Pick-offs 16, 16A, 16B actuated by the control member 6 contact with the potentiometers 8, 8A, 8B and pick-offs 17, 17A, 17B actuated by the cylinder 4 contact with the potentiometers 10, 10A, 10B.

If desired, signals may also be fed to the transducers via the amplifiers 9, 9A and 9B from an auto-pilot and/or from an auto-stabilizer. Also, provision may be made as described in British application No. 36147/54 for reversion to mechanical control of the jack by the pilot in the event of an emergency.

It is necessary that each of the amplifiers 9, 9A, 9B should saturate at an input level proportional to a misalignment between the input and output members of the servo motor small in relation to the total stroke of the output member.

If desired, each of the three-coil transducers illustrated may be replaced by three single-coil transducers, each fed from one of the amplifiers. Also, the transducer mechanisms may, if desired, be fed with signals from more than three electrical signalling systems operable by the pilot's control member.

Again each section of the jack may be provided with more than two independently movable control valves, each of which is actuatable by the pilot through the agency of an associated electro-mechanical transducer mechanism. Moreover, four or more electrical signalling systems may be provided, signals from all of the electrical systems being fed to each of the transducer mechanisms. Thus each section of the jack could have three control valves, each actuated by a four-coil transducer receiving signals from four electrical systems operable by the pilot's control member.

The number of control valves per section of the jack must be at least two and may either be equal to or may exceed the number of electrical signalling systems.

The operation of the system is as follows:

On movement of the pilot's lever 7 corresponding signals are sent from the potentiometers 8, 8A, 8B to the corresponding amplifiers 9, 9A, 9B. Each of the electrical signalling systems then sends from its associated amplifier signals to all of the transducers 6, 6A, 6'A and 6' demanding movement of their associated control valves 5, 5A, 5'A and 5' in the direction corresponding to the direction of movement of the pilot's lever 7. The amplifier 9 supplies such signals to the coils numbered 12, the amplifier 9A to the coils numbered 13 and the amplifier 9B to the coils numbered 14 as will be clear from Fig. 1. As the result of movement of the four control valves 5, 5A, 5'A and 5' the cylinder block 4 of the jack moves in the same direction as the control valves to effect appropriate movement of the control surface 1. As the result, the potentiometers 10, 10A, 10B send feed back signals to the amplifiers 9, 9A, 9B and, when the control surface 1 has assumed the position demanded by the pilot's lever 7 the control valves are returned, by the transducers under control of the amplifiers, to their neutral position,

illustrated in Fig. 1, to prevent further movement of the jack.

If any of the control valves should stick in an open position, e. g. if the valve 5 should remain displaced to the right from its neutral position, the other three control valves will not be returned precisely to their neutral positions and will assume a position slightly to the left of their neutral positions so producing a hydraulic load on the jack balancing that produced by the open valve 5.

If any two of the electrical signalling systems should fail to operate, e. g. the systems associated with the amplifiers 9A and 9B, the remaining system associated with the amplifier 9 will still be able to supply signals to all of the transducers via the coils numbered 12, so enabling the pilot to retain control over the jack. Even if a fault should develop in one of the electrical signalling systems, e. g. that associated with the amplifier 9B, which results in transmission to the coils numbered 14 demanding movement of the control valves in the reverse direction to that selected by the pilot, the coils numbered 12 and 13 of each transducer which receive signals from the still effective electrical systems will be able to overpower the defective coils numbered 14 and ensure that the control valves will be moved in the correct direction.

What we claim as our invention and desire to secure by Letters Patent is:

1. A power operated flying control system for aircraft, comprising a control surface, a tandem hydraulic jack comprising two cylinders, a piston in each cylinder, a piston rod connecting said pistons, and at least two independently movable control valves adjacent to each cylinder and controlling the admission of fluid thereto and the exhaust of fluid therefrom, means actuated by relative movement of said cylinders and pistons for imparting movement to said control surface, a plurality of electro-mechanical transducer mechanisms, one for operating each control valve, a pilot's control member and an electrical signalling system connected to all of said transducer mechanisms and operable by said control member to transmit signals to all of said transducer mechanisms and thereby to actuate said jack to position said control surface in correspondence with the position of the control member.

2. A power operated flying control system for aircraft, comprising a control surface, a tandem hydraulic jack comprising two cylinders, a piston in each cylinder, a piston rod connecting said pistons, and at least two independently movable control valves adjacent to each cylinder and controlling the admission of fluid thereto and the exhaust of fluid therefrom, means actuated by relative movement of said cylinders and pistons for imparting movement to said control surface, a plurality of electro-mechanical transducer mechanisms, one for operating each control valve, a pilot's control member and at least three electrical signalling systems, each of said signalling systems being connected to send signals under control of the pilot to all of the transducer mechanisms and all of said signalling systems being operable in common by the pilot's control member to transmit signals to all of said transducer mechanisms and thereby to actuate said jack to position said control surface in correspondence with the position of the control member.

3. A system as claimed in claim 2, in which each transducer mechanism comprises a movable armature connected to the associated control valve and a plurality of coils controlling the position of said armature, each coil being connected to and receiving signals from one of said signalling systems.

4. A system as claimed in claim 2, in which each electrical signalling system comprises an amplifier, a pair of potentiometers, an individual source of electric power for energizing said amplifier and said potentiometers, means operated by the control member for adjusting one potentiometer to supply input signals to the amplifier and means actuated by the jack for adjusting the other potentiometer to supply feed back signals to the amplifier.
